3 Claims. (Cl. 102—78)

1

This invention relates to fuzes having a mechanical delay device.

Numerous types of fuze are already known which are designed to be mounted in the ogival head, inside or at the base of explosive projectiles, and which comprise devices intended to ensure security against shock during storage or handling, security in the bore on firing, to give delayed arming in order to avoid premature bursting of the projectile if the latter should, after discharge, encounter an unexpected obstacle, such as camouflage, branches, or the like, in the vicinity of the firer, and, moreover, to ensure on impact either instantaneous or delayed bursting.

Such fuzes generally comprise a fairly complicated mechanical device, the functioning of which is controlled either by a clockwork movement or directly by the forces acting on the projectile on the firing of the shot.

The present invention relates to fuzes complying with the above-mentioned conditions and with all requirements, while being of simple construction, capable of being made of very small dimensions, comprising a minimum of parts, being adapted to resist the stresses developed on the discharge of the shot, and, if so required, to resist the impact shock.

The fuzes of the present invention are of the type which are provided with a mechanical arming delay device, or mechanical safety or firing device, comprising essentially two co-acting parts, one of which comprises at least one groove and the other at least one slide adapted to run in said groove, and are characterized by the fact that one of said co-acting parts is an inertia block maintained in a safety position by the action of at least one opposing member, and that the groove comprises two converging branches disposed substantially in the shape of a V and imposes on the slide forming the bolt, at least in one of its branches, a zig-zag path, so that, under the action of a sustained thrust greater than the action of the opposing member, said inertia block passes from the safety position to an intermediate position, the slide being caused to fork from one of the branches of the groove into the other; the inertia block can from that moment reach the armed position when the thrust effect greater than the action of the opposing member ceases, its displacement having taken place first in one direction, in accordance with one of the branches of the groove, then in the opposite direction, under the opposing force, in accordance with the other branch of the groove; said zig-zag path having thus slowed down the displacement of the

2

inertia block in imposing it a rotary oscillating movement.

The opposing member can be an elastic opposing member such as, for instance, a spring.

With such a device, security against shock during storage and handling of the projectiles, as well as security in the bore of the gun on firing, and muzzle safety are absolute, since no accidental force can act on the inertia block simultaneously in the axial direction and in the tangential direction, nor for a sufficiently long space of time to cause the slide to follow, first in one direction and then in the other, the zig-zag V-shaped path presented by the groove, which can only take place after the shot has been fired and within the period of time corresponding to the desired delay.

The length of the groove, the number and extent of the zig-zags, the diameter and the weight of the inertia block are so many factors which can be varied at will in order to increase or decrease the desired effect, which is to delay the moment when the arming of the fuze or the ignition takes place.

The fuze can be designed with consideration to the characteristics of the equipment serving to discharge the projectile, the value of the charges employed, the pressures and the accelerations given to the firing of the shot, while assuring either time operation or impact operation, or again, while providing the desired bursting effects such as instantaneous or delayed burst.

According to one feature of the invention, the aforesaid groove comprises two unequal branches, one at least of which is blind, that is to say ends in a cul-de-sac. The longer of said branches is preferably open at the end. In the position of rest, or the safety position, the slide forming the bolt preferably abuts against the end of the blind branch, the inertia block being immobilised in that position by the thrust of the opposing member, for example a spring, which tends to keep the slide abutting thereagainst.

Under the action of a sustained thrust greater than the action of the opposing member, such as a positive or negative acceleration, the inertia block is displaced, following the oscillating movement imposed on it by the zig-zag shape of the groove, and the slide proceeds to occupy at the point of the V the intermediate position in which it is engaged in the long branch of the groove. When the thrust or acceleration action ceases, the opposing member reacts, pushing back the inertia block in the opposite direction, while the slide runs along said branch of the groove, escap-

ing at its end and completely liberating the inertia block.

In the event of the projectile being accidentally dropped, or in the event of its sustaining a shock in such a direction that the effect is added to the action of the opposing member, the slide is held with greater force in the safety position at the bottom of the blind groove, and the inertia block does not move.

If the accidental shock takes place in the opposite direction, only a slight displacement of the inertia block results; as the latter is subjected, during this displacement, to the zig-zag movements imposed on it by the groove, it will be stopped by the fact that an axial shock cannot give rise to the necessary rotary lateral movement, and the opposing member will bring back the inertia block to its original safety position before the slide reaches its intermediate position at the point of the V formed by the groove.

This device, used for example to bring about delayed arming and mechanical functioning in an ogival fuze, is also suitable, by simple inversion or change of direction, for carrying out similar functions in a base fuze, or again in a firing device located inside the projectile.

Thus, in one particular embodiment of the invention, the groove comprises a long branch and a blind cavity in which the slide is adapted to engage in such manner as to lock the inertia block, under the action of the opposing member, when it comes into the armed position.

In this case, the slide first runs along the long branch of the groove under the action of a thrust, such as the propulsive force of the projectile, and then, when said thrust ceases, it is pushed back by the action of the opposing member into the blind cavity, which replaces the short branch of the groove, and thus immobilises the inertia block, which has come into the armed position.

In accordance with a further feature of the invention, the fork of the two branches of the groove is disposed in such manner that one of them, preferably the blind branch, joins the other laterally.

In this manner the slide, when it has run along one of the branches of the groove, engages in the other before or on abutting against the point of the V, and cannot re-enter the branch that it has just left; forking from one branch into the other is thus ensured in certain manner.

It may be desired that the displacement of the inertia block under the action of the opposing member should be rapid and undelayed when the slide leaves its intermediate position.

In this case, the long branch of the groove will be rectilinear and preferably disposed in the axial direction, only the blind branch being zig-zag in shape.

In order to reduce the effects of inertia and to avoid all risk of caulking, deformation, and parasitic friction liable to affect the efficiency of operation of the device when it is desired that the latter should be able to resist very violent forces or shocks, for example on the firing of the shot, provision has been made, according to still a further feature of the invention, to increase the number of the zig-zags and to decrease their pitch, to such an extent as to give to at least one branch of the groove a generally undulatory outline.

Moreover, in order to ensure, simply and perfectly, the passage of the slide from one branch of the groove into the other, and to avoid lateral tension of the opposing member, particularly if

a spring is involved, the branches of the groove are disposed in such a manner that the safety position and the intermediate position of the slide are on the same longitudinal axis.

It is naturally understood that the use of a lateral tension of the spring to ensure the functioning of the device is in no way excluded.

In one embodiment, the slide is a finger integral with one of the two co-acting pieces.

In another embodiment, a ball partially imprisoned in a groove provided in one of the two co-acting pieces attends to the same function.

Convenient solutions can be found for numerous problems by the practical application of devices complying with the features of the invention, among them, in particular, the following different cases:

20 A device comprising a cap-carrying inertia block provided with a groove in accordance with the invention;

25 A device comprising a cap-carrying inertia block provided with a slide in accordance with the invention;

25 A device comprising a striker-carrying inertia block provided with a groove in accordance with the invention;

30 A device comprising a striker-carrying inertia block provided with a slide in accordance with the invention;

35 A device comprising a cap carrier-detonator adapted to pass from an inactive safety position relative to the explosive charge of the projectile to an active position in which the transmission of the explosion can take place normally on impact.

35 In one example of a fuze corresponding to the features of the invention, two concentric co-acting inertia blocks are provided, one of which is immobilised in the safety position in the body of the fuze, through the medium of a yielding member, such as a ball, the liberation of which is dependent on the functioning of the other inertia block, which is subject to the action of the opposing member.

40 Retarded arming on firing of the shot is thus simply obtained in an instantaneous percussion fuze for projectiles propelled by a gun or acquiring their speed through a self-propelling charge and provided with a percussion head adapted to be driven back on impact.

45 The external inertia block can be disposed in such manner as to give, in the safety position, supplementary protection to the cap set back in the internal inertia block.

50 The invention also enables a very simple fuze to be designed for projectiles propelled by a gun or by self-propulsion, the arming of which takes place only on impact, the functioning of the fuze taking place through delayed percussion, only after braking and stopping of the projectile in the ground or any other objective, the opposing member being disposed in such manner that it reacts on the inertia block only on impact, the delay being produced at that moment.

55 Finally, the device of the invention can also be utilised to liberate, with delay, an obturator designed to prevent transmission of fire prematurely.

60 In this case, the inertia block can take the form of an obturating bell which, in the safety position, covers the piece with which it co-acts through the medium of the slide and groove of the invention, said bell preventing the transmission of fire until it is ejected by the action of the opposing member.

65 Other advantages and features of the inven-

tion will become apparent from the following description.

In order to enable the invention to be more readily understood, reference is made to the accompanying drawings which illustrate diagrammatically and by way of example, various embodiments thereof, and in which:

Figs. 1 to 7 inclusive represent in axial section a fuze in accordance with the invention and, in front view, its inertia block provided with grooves, in the various stages of operation;

Figs. 8, 9 and 10 show a fuze comprising a mobile detonator, in the safety position and in the armed position, as well as its inertia block;

Figs. 11 and 12 represent respectively a fuze intended to be placed inside a projectile, and its inertia block;

Figs. 13 and 14 illustrate respectively an inertia fuze with delayed arming, and its inertia block;

Figs. 15 to 22 inclusive represent respectively various modifications of devices according to the invention, comprising an inertia block forming a bell designed to prevent premature firing;

Fig. 22a shows an application of the device represented in Figs. 15 and 22.

Figs 23 to 27 inclusive represent respectively in various stages of operation, a fuze designed to function with delayed percussion, together with its inertia block.

In order to facilitate understanding, parts serving the same purpose in each of the various figures have been designated by the same reference numerals.

The fuze illustrated in Figs. 1 to 7 is composed of a fuze body 1 provided in front with a percussion head 2, with a striker 3 and, at the rear, with a detonator 4. An inertia block 5 provided with a cap 6 and subject to the action of a compression spring 7, which acts as opposing member by bearing against a rear rest 8 on the fuze body, is adapted to move axially in a cylindrical cavity 9 provided in the member co-acting with said inertia block 5. This co-acting member is generally the body 1 itself; in the embodiment illustrated in Figs. 1, to 7, this member is a second inertia block 10 concentric with the inertia block 5 and resting, in the safety position, on an annular projection 11 on the body 1; this second inertia block 10 is disposed to be movable axially inside a cylindrical cavity 12 formed by the fuze body 1.

Union between the two inertia blocks 5 and 10 which are co-acting and concentric is achieved, according to the invention, by means of a slide 13 integral with the external inertia block 10 and adapted to run along a groove 14 hollowed out in the periphery of the internal inertia block 5.

The groove 14 (Fig. 2) comprises two branches of unequal lengths 14a and 14b, disposed in the shape of a V and providing a zig-zag path for the slide 13. The long branch 14a is open at its end 15, while the short branch 14b is blind, that is to say ends in a cul-de-sac at 16. The blind branch 14b runs laterally into the long branch 14a, near the end 17 of the latter, in such manner that the slide 13, when it is engaged in the long branch, can no longer go back into the blind branch.

A ball 18 lodged in aperture 19 in the external inertia block 10 (Fig. 1) projects from its aperture, in the safety position, and is engaged in a circular recess 20 provided inside the cylindrical cavity 12, thus immobilising said inertia block 10 with the slide 13 when in the safety position.

The spring 7 for its part holds the grooved inertia block 5 against the bottom of the blind groove 14b in the slide 13 acting as bolt.

The outer inertia block 10, which serves as seating for the inner cap-carrying inertia block 5, is adapted to act as a stop for the head 2 carrying the striker in the event of said head being accidentally driven into the interior of the fuse body 1; to this end, said inertia block 10 is sufficiently long so that the striker point 3 can in no case come into contact with the cap 6 as long as the latter is in the safety position (Fig. 1), withdrawn in the cylindrical cavity 9.

The striker-carrying head 2 is immobilised by a pin 21 shearable on impact, or by any other means, such as, for example, a circular stop (not shown in the drawings) resting on a thin washer, which is likewise shearable on impact.

Complete tightness of the fuse is obtained by means of an elastic mass 22, consisting of cork, for example, and acting as a stopper at the extremity of the cylindrical cavity 12.

A spring 23, completely expanded, is placed in the housing constituted by the front part of the cylindrical cavity 12, between the internal face 24 of the striker-carrying head 2 and a shoulder 25 on the outer inertia block 10. This very weak spring 23 serves to keep the unit comprising the two inertia blocks 5 and 10, and therefore the cap 6, at a distance from the striker point 3 when the fuze is armed, and enables the fuze to be given extreme sensitiveness to impact.

In the event of dropping, or if there should be a blow on the fuze head, with sufficient force to shear the pin 21, while the inertia blocks 5 and 10 are in the safety position (Fig. 1), the striker-carrying head can without danger strike with its face 24 against the extremity 26 of the inertia block 10, because the striker point 3 is too short to reach the cap 6. The cap-carrying inertia block 5 itself, being immobilised by the slide 13 at the bottom of the path in the blind groove 14b (Fig. 2), cannot move forward; percussion is therefore impossible.

In the case of a blow in the opposite direction, the slide 13 acts as a bolt in the zig-zag groove 14 under the thrust of the spring 7, and thus these three members resist any substantial displacement of the cap-carrying inertia block 5, which immediately returns to bear against the slide 13 at the bottom of the blind groove, at 16.

The mode of operation of the fuze illustrated in Figs. 1 to 7 is as follows:

On the firing of the shot, the inertia block 5, through inertia under the propulsive action, compresses the spring 7 and moves backwards to bear against a circular flange 27 on the fuse body 1, taking up the position shown in Fig. 3, while the slide 13, running along the blind branch 14b of the groove 14, takes up its position at the point 17 of the V (Fig. 4), where it is engaged in the long branch 14a, in the intermediate or pre-arming position. From that moment it can no longer re-enter the side branch 14b that it has just left.

When the positive acceleration ceases, the spring 7 pushes the cap-carrying inertia block 5 forward again, the slide 13 then making use of the long branch 14a of the groove, the zig-zag shape of which obliges said inertia block to perform on its axis an oscillating movement which slows down its axial displacement, while the outer inertia block 10 still remains immobilised in the fuze body 1 by the ball 18 imprisoned in the aperture 19 and in the recess 20.

Before reaching the front extremity of the cylindrical cavity 9, the inertia block 5 releases the ball 18, which escapes to the interior (Fig. 5), and then the slide 13, which emerges through the open end 15 of the groove 14a. The outer inertia block 10, being released, is in turn carried along axially by the inner inertia block 5 as soon as the latter strikes against a rim 28 on the inertia block 10, causing the cap 6 to project forwards through the latter.

When the parts are in this position, the fuze is armed, the striker 3 and the cap 6 being held apart from one another only by the weak resistance of the spring 23, while the spring 7 is completely extended.

From that moment percussion is ensured on impact, either by the driving back of the striker-carrying head 2 after shearing of the pin 21 (Fig. 6), or by inertia, the cap-carrying inertia block 5 and the outer inertia block 10 both moving forwards towards the point of the striker in the event of striker-carrying head 2 not having been driven back by the objective (Fig. 7).

Figs. 8 to 10 illustrate a shell fuze capable of ensuring at the same time complete safety during storage and on firing, including prevention of any rebound, with displacement of the detonator cap which passes from an inactive safety position relative to the explosive charge of the projectile to an active position, in which the explosive transmission can normally be produced on impact.

A fuze body 1, bored from end to end with a single diameter, carries slides 13 serving as stop and control fingers and disposed in such a manner as to be able to slide in the corresponding grooves 14 provided, in accordance with the invention, in an inertia block 5 placed at any desired distance inside the body 1.

Each groove 14 (Fig. 9) comprises two branches 14a and 14b disposed in the shape of a V, which provide a zig-zag path for the appertaining slide.

A spring 7 applies at one end a pressure against the inertia block 5, which keeps it bearing against the slides 13 at the bottom of the blind grooves 14b, and, at the other, keeps the detonator 4, mounted on a second inertia block 10, bearing against the rear end 29 of the fuze body 1.

A spring 38, decidedly weaker than the spring 7, remains compressed in the waiting position between the lower surface 31 of the inertia block 10 and the bottom 29 of the fuze body.

A striker-carrying stopper 2, placed in the head of the fuze body 1, attends to the sealing of the latter; this stopper is provided with an extended striker 3, which passes right through the grooved inertia block 5 and enters the interior bore 9 of the cap-carrying inertia block 10, at the base of which is located the cap 6.

In the case of an accidental blow on the fuze, the grooved inertia block 5 will react as described above and ensure the absolute safety of the device.

On the firing of the shot, said inertia block 5, under the influence of the propulsive effect and through inertia, causes the spring 7 to yield, travels backwards in a reciprocating rotary movement imposed on it by the branches 14b of the grooves, and the slides 13 move to the point of the V, at 17 (Fig. 9).

After firing, at the end of the propulsive thrust, the spring 7 returns the inertia block 5 forwards, the slides 13 then each utilising respectively the zig-zag paths of the grooves 14a. By reason of the backward and forward travel, displacement of the inertia block towards the front is slowed down

until the slides 13, reaching the end 15 of the grooves 14a, escape from the latter. At that moment, no longer under the influence of the spring 7, which is extended, but under that of the spring 30, the parts take up the armed position illustrated in Fig. 10. Percussion on impact is from that moment ensured.

The device forming the subject of the invention can also be utilised in such manner as to operate a pyrotechnical or mechanical time fuze, as illustrated in Fig. 11.

The fuze body 1, bored throughout its length, is provided with a detonator-carrying head 2 carrying a cap 6 and a detonator 4. A slide 13, integral with the body 1, is engaged in the safety position in the blind branch 14b of a V-shaped zig-zag groove 14 disposed on a striker-carrying inertia block 5 which a spring 7, bearing on the base 29 of said body, holds against the slide 13 at the bottom of the blind groove 14b.

In the case of accidental shock, the striker-carrying inertia block 5 is held in the safety position, as hereinabove described, by the combined action of the slide 13, the groove 14, and the spring 7.

On the firing of the shot, the striker-carrying inertia block 5, under the influence of the propulsive effect and following the movements imposed on it by the zig-zag groove 14b, compresses the spring 7 until the slide 13 reaches the end of the blind groove, where it forks into the long groove 14a. As soon as the propulsive effect ceases, the spring 7 returns the inertia block forwards; it then follows the movements imposed on it by the long branch 14a of the groove, and then, when the slide 13 reaches the outlet 15 of the latter, it is released and is thrown by the spring 7 towards the cap 6, in which its point penetrates and gives rise to the firing.

Fig. 12 shows that the blind branch 14b of the groove may, like the long branch 14a, have several successive zig-zags, the effect of which is to increase the delay and not to permit the slide 13 to assume the pre-arming position 17 except under a longer thrust effect.

Figs. 13 and 14 relate to a device combined in such a manner as to obtain an inertia fuze with delayed arming, for projectiles preferably propelled by self-propulsion.

The fuze comprises a body 1 in which are housed a grooved inertia block 5 provided with a striker 3, a cap-carrying inertia block 10 provided with a cap 6 and a detonator 4, and a spring 7 bearing at one end on the striker-carrying inertia block and, at the other end, on the cap-carrying inertia block. In the safety position, the spring 7 tends to keep the two inertia blocks apart from one another. The total path available to the cap-carrying inertia block 10 as far as a stop 32 provided on the fuze body does not enable the cap to touch the striker point.

Since, moreover, the striker is immobilised, as hereinbefore described, by the combined action of slides 13 on grooves 14 and of the spring 7 on the grooved inertia block 5, security against shocks, either on the nose of the fuze or in the opposite direction, is assured.

In this particular case, the blind branch 14b of the groove 14 is reduced to a blind cavity 16 adapted to receive the slide 13 at the end of the path, said slide being located at the entrance 15 of the long branch 14a (Fig. 14), as long as it is in the safety position.

On the firing of the shot, under the influence of the propulsive effect the striker-carrying

inertia block 5, the mass of which is effective in direct proportion to the acceleration given, oscillates on its longitudinal axis by following the movements imposed on it by the zig-zags of the long branch 14a of the groove, and compresses the spring 7, being displaced towards the rear until the slide 13 has reached the extremity 17 of said groove.

As soon as the propulsive effect ceases, the spring 7 returns the inertia block 5 in the opposite direction; the slide 13, taking up position in the cavity 16 which forms a stop, thus keeps the striker 3 held in such manner that, on impact, the point 3 will penetrate the cap 6 when the cap-carrying inertia block 10 meets it.

In one particular embodiment of the invention, the device of the invention may also be utilized to release, with delay, an obturator designed to prevent premature transmission of firing (Fig. 15).

Inside a suitable jacket 1, an inertia block 5 forms an obturation bell and carries a slide 13 in the form of a stop and control finger. The bell inertia block 5 fits over and caps a projection forming a support 33, which constitutes the co-acting member and carries the zig-zag groove 14 (Fig. 16), and has the central aperture 33a through which fire can pass to the detonator.

An ejection spring 7 in this aperture holds the bell inertia block 5 against the slide 13 at the bottom of the blind groove 14b of the support 33.

In this safety position, the bell prevents the transmission of firing or of the explosive wave from the cap of a fuze located in the front or nose end of the projectile.

On the firing of the shot, the bell inertia block 5, under the influence of the propulsive effect and through inertia, follows the movements imposed on it by the blind groove 14b, compressing the spring 7 until the end of the path of the slide 13 in said groove, said slide then taking up position at 17.

As soon as the propulsive effect ceases, the spring 7 returns the obturation bell 5 to the front; said bell then follows the movements imposed on it by the zig-zags of the long branch 14a of the groove in which the slide 13 runs, and then, when the latter reaches the outlet 15 of said groove, the bell is ejected by the spring 7, thus freeing the fire passage orifice. Transmission of firing may take place from that moment on.

The specific structure shown in Fig. 15 has the body 1 formed with a cylindrical inner wall spaced from the projection or support 33 to provide an annular cavity in which is closely received the cylindrical skirt 5b of the obturator bell. The externally conical closed forward end 5a of the bell is thicker than the lateral skirt wall 5b. The illustrated arrangement has the technical advantage of increasing the safety factor of the mechanical delay device. Thus, if premature fire from a nose primer of a fuze 37 (Fig. 22a) is projected against the head 5a, while the obturator is in safety position, the fire is compelled to follow a tortuous path between the wall 1 and the skirt of the obturator bell 5, and then between this skirt and the coaxial projection 33, and finally through the central aperture or passage in the projection 33. The illustrated shaping and proportioning of the closed forward end provides greater heat absorption and resistance to perforation during the brief firing period of the primer cap.

Fig. 17 illustrates a modification of the device illustrated in Fig. 15, in which modification the slide 13 is integral with the jacket 1, while the groove 14 is carried by the bell inertia block 5 and is disposed in the opposite direction (Fig. 18). The mode of operation is the same as in the case of Fig. 15.

In the modification illustrated in Fig. 19, the general disposition is the same as in the case of Fig. 15, but it comprises two grooves disposed in such manner that the ejection of the bell inertia block 5 is instantaneous when the slide 13 is caused to leave its intermediate position. This result is obtained by giving the long branch of 14a of the groove a rectilinear shape, while only the blind branch 14b has zig-zags (Fig. 20). The spring 7 being very weak in order to give the device great sensitiveness, the branch 14b of the groove has been made longer than hitherto in order to force the slide to travel over a longer zig-zag path before reaching the intermediate position 17.

In addition, by way of example, the slide is designed in the form of a ball 13 imprisoned in a recess 34 in the bell inertia block 5, which gives it greater flexibility in operation.

In order to enable the device to resist even very violent shocks, either during handling or on the firing of the shot, and to avoid all risk of caulking, deformation, or parasitic friction liable to impair good operation, provision has been made, in the arrangement illustrated in Fig. 21, for a greater number of backward and forward movements in the groove 14, while reducing the length of each such movement. The branches 14a and 14b of the groove thus assume a generally undulatory shape.

The grooves may also be disposed in the manner illustrated in Fig. 22, so that the safety position 16 of the slide 13 and its intermediate or pre-arming position 17 are in the same longitudinal axis X—X. While ensuring in perfect fashion the passage of the slide 13 from the groove 14b into the groove 14a, this enables all lateral tension of the return spring 7 to be avoided in the event of that occurring in consequence of the oblique position of the groove.

Fig. 22a shows how the obturator device described in connection with Fig. 15 may be employed in a projectile 41 having a cavity 42 between the front end and the obturator 5. The primer cap in an impact fuze 37 at the nose of the projectile is to be fired on impact, transmitting its fire or explosive wave rearward through this cavity along the axis of the projectile; but so long as the obturator bell 5 is in safety position, the detonator 38 is not energized. Thus, the device is safe against explosion of the charge 39, 40 prior to the normal propulsion of the projectile. During the early part of the trajectory of the projectile, the obturator bell 5 moves rearward from its safety position, with its slide 13 passing from the full line position to the dotted line position of Fig. 22, for example. When the positive acceleration of the projectile drops, the sustained thrust falls below the effort of the spring 7, and this spring then acts to move the bell 7 relatively forward, with the slide 13 passing along the second or open-ended branch 14a of the groove. Ultimately, the spring 7 ejects the bell 5, for example along the path shown by dotted lines in Fig. 22a, thereby uncovering the aperture through the projection 33 (Fig. 15) and permitting the fire from the primer cap of fuse 37

then to have passage through the aperture to the detonator 38 for energizing the same, whereby with the explosive charge 39, 40 is detonated.

The device forming the subject of the invention also renders it possible to provide, for projectiles discharged by guns or by self-propulsion, a very simple fuze the arming of which takes place on impact, operation by delayed percussion taking place only after braking or stoppage of the projectile in the ground or any other objective.

Figs. 23 to 27 relate to such a device. A cap carrying fuze body 1 of great strength carries the slide or slides 13, the groove or grooves 14 being placed on a striker-carrying inertia block 5; a spring 7 holds said inertia block, in the safety position, against the slide 13 at the bottom of the blind groove 14b (Figs. 23 and 24). A supplementary stop, for example consisting of balls 35, may if desired be provided (Fig. 27) if firing is to take place with very great accelerations on discharge of the shot.

Safety in the position of rest is ensured by the cooperation of the slide 13, the groove 14b, and the spring 7, in the same manner as hereinbefore described.

On the firing of the shot, the position of the parts remains unchanged. On impact, the projectile loses its speed and, after penetration to a greater or lesser degree, depending on the resistance of the target, is completely stopped. In consequence of this braking effect, the striker-carrying inertia block 5, owing to its residual kinetic energy, is carried forward, compressing the spring 7 (Fig. 25).

In the embodiment illustrated in Fig. 27, the balls 35, released when the inertia block 5 moves forward, leave their annular housing 36 and take up position behind the inertia block.

As soon as the projectile has stopped, the spring 7 returns the inertia block 5 to the rear, the zig-zag groove 14a first imposing on it a slow movement after which, when the slide 13 leaves said groove, the spring 7 throws the striker-carrying inertia block 5 against the cap 6, which fires.

What I claim is:

1. A mechanical safety delay device for a projectile fuze having a body with an aperture through which fire is to be transmitted as an incident of detonation, comprising two main co-acting parts, one of which parts is an ejectable obturator and the other part is a body projection having said aperture extending therethrough, said obturator part having the shape of a bell and being located when in safety position around said projection and covering the aperture and thereby preventing the transmission of fire, one of said main co-acting parts having at least one groove formed by two converging branches, the other of said co-acting parts having a sliding member adapted to run in said groove, one branch of said groove having a blind end for receiving the sliding member when in safety position and preventing forward movement of the said obturator part, said one branch having a zig-zag shape for co-acting with the sliding member during positive acceleration of the projectile and thereby effecting a slowing down of the inertial relative rearward movement of the obturator part by rotary oscillating movements imparted thereto, the converging point of said branches being axially aligned with the said other branch thereof so that a forward movement of the obturator part after

the sliding member has come to the converging point will cause the sliding member to enter the said other branch, said other branch having an open end remote from said converging point whereby the sliding member is released by the groove during forward movement of the obturator part while the member is moving along said other branch, and therewith the obturator is ejected from its covering position, and an opposing member effective to maintain said obturator part normally in a safety position prior to the positive acceleration of the projectile.

2. A mechanical safety delay device for a projectile fuze having a body with an aperture through which fire is to be transmitted as an incident of detonation, comprising two main co-acting parts, one of which parts is an ejectable obturator and the other part is a body projection having said aperture extended therethrough, said obturator part having the shape of a bell with the forward end thereof being a head of external conical shape and having greater thickness than the lateral wall portion of said bell, the bell being located when in safety position around said projection and covering the aperture and thereby preventing the transmission of fire, one of said main co-acting parts having at least one groove formed by two converging branches, the other of said co-acting parts having a sliding member adapted to run in said groove, one branch of said groove having a blind end for receiving the sliding member when in safety position and preventing forward movement of the said obturator part, said one branch having a zig-zag shape for co-acting with the sliding member during positive acceleration of the projectile and thereby effecting a slowing down of the inertial relative rearward movement of the obturator part by rotary oscillating movements imparted thereto, the converging point of said branches being axially aligned with the said other branch thereof so that a forward movement of the obturator part after the sliding member has come to the converging point will cause the sliding member to enter the said other branch, said other branch having an open end remote from said converging point whereby the sliding member is released by the groove during forward movement of the obturator part while the sliding member is moving along said other branch, and therewith the obturator is ejected from its covering position, and an opposing member effective to maintain said obturator part normally in a safety position prior to the positive acceleration of the projectile.

3. A mechanical safety delay device for a projectile fuze having a body with an aperture through which fire is to be transmitted as an incident of detonation, comprising two main co-acting parts, one of which parts is an ejectable obturator and the other part comprises a body projection having said aperture extended therethrough and a peripheral cylindrical wall spaced from and concentric with said projection, said obturator part having the shape of a bell with a cylindrical skirt closely fitting and movable in the space between said projection and said wall, said bell when in safety position covering the aperture in said projection and thereby preventing the transmission of fire through said aperture, one of the said main co-acting parts having at least one groove formed by two converging branches, the other of said co-acting parts having a sliding member adapted to run in said groove, one branch of said groove having a blind end for receiving the sliding member when

in safety position and preventing forward movement of the said obturator part, said one branch having a zig-zag shape for co-acting with the sliding member during positive acceleration of the projectile and thereby effecting a slowing down of the inertial relative rearward movement of the obturator part by rotary oscillating movements imparted thereto, the converging point of said branches being axially aligned with the said other branch thereof so that a forward movement of the obturator part after the sliding member has come to the converging point will cause the sliding member to enter the said other branch, said other branch having an open end remote from said converging point whereby the sliding member is released by the groove during forward movement of the obturator part while the member is moving along said other branch, and therewith the obturator is ejected from its covering position, and an opposing member effec-

tive to maintain said obturator part normally in a safety position prior to the positive acceleration of the projectile.

EDGAR WILLIAM BRANDT.
